UNITED STATES PATENT OFFICE.

JOSEPH F. BATCHELOR, OF NEW YORK, N. Y., ASSIGNOR TO ELIZA J. BOYDEN, OF NEWARK, NEW JERSEY.

VALVE-ACTUATING DEVICE.

SPECIFICATION forming part of Letters Patent No. 633,415, dated September 19, 1899.

Application filed June 14, 1898. Serial No. 683,449. (No model.)

To all whom it may concern:

Be it known that I, JOSEPH F. BATCHELOR, of New York, (Brooklyn,) State of New York, have invented a certain new and useful Improvement in Valve-Actuating Devices, of which the following is a specification.

This invention relates in general to those means for controlling the flow of steam or other fluid which embrace in combination with a valve-head an actuating-piston.

The invention includes, associated with the foregoing elements, a secondary valve or equivalent device which serves the purpose of admitting the steam or other fluid to and exhausting it from the chamber containing the said piston either directly or through the intervention of other mechanism.

It is a further purpose of the improvement to provide a secondary valve of a balanced character such that a minimum effort is required to operate it.

I will describe a valve-actuating device showing the features of my invention, subsequently pointing out the novelty of the latter in the claims.

In the accompanying drawings, Figure 1 is a side view, mainly in elevation, of a valve-actuating device embodying my invention, certain parts being removed the better to show parts lying beyond. Fig. 2 is a longitudinal vertical section through the device represented in Fig. 1. Fig. 3 is a view, partly in elevation and partly in section, of the secondary valve embraced in the device of Figs. 1 and 2, showing said valve as arranged to be operated either mechanically or electrically. Fig. 4 is an enlarged view of the secondary valve, showing the means of balancing the same. Fig. 5 is a side elevation of the valve device in a modified form. This view shows an alternative form of construction for operating the secondary valve. Fig. 6 is a vertical section through Fig. 5. Fig. 7 is a sectional elevation representing in detail the construction for operating the secondary valve represented in Fig. 5. Fig. 8 is an enlarged view of the balanced secondary valve shown in Fig. 7.

Similar letters of reference designate corresponding parts in all the figures.

Confining the description at first to the de-

vice exemplified in Figs. 1, 2, 3, and 4, A represents a valve-casing provided with an inlet-opening a and an outlet-opening a' , both of which openings may be tapped, as usual, to receive the threaded ends of connecting-pipes. The main-valve head is represented at A', co-operating with a suitable seat a^2 and rigidly connected by a stem B with a piston B', which is fitted to a cylinder b, formed by a bonnet 55 detachably connected with the valve-casing. The stem B is hollow, and to its cylindrical bore there is fitted the fluted spindle b^2 of the auxiliary valve C. The seat of the auxiliary valve C is formed at the extremity of said bore on the main-valve head. The auxiliary valve moves to and fro in the tubular extension c, projecting from the face of the main-valve head. This extension is provided with transverse openings c' , such that when the auxiliary valve is moved from its seat the steam or other fluid may find its way inward through the opening c' and thence to the rear of the piston B' by way of the flutings or channels in the valve-spindle b^2 . The space at 60 the front of the piston B' is of course open to the atmosphere by suitable passages c^2 .

For the purpose of moving the auxiliary valve from its seat I have provided on the spindle of the same the secondary piston D, 80 which is fitted to slide to and fro in the cylinder d. In this instance as well one or more openings d' will place the space at the front of the piston D in constant communication with the atmosphere.

For the purpose of limiting the distance the main-valve head A' moves from its seat an adjustable stop E enters the valve-casing and is provided with a shoulder e, against which the end of the tubular extension c impinges 90 when the main-valve head A' is thrust from its seat by the movement of the piston B'. If this stop is fitted at its inner extremity to the bore of the tubular extension c, it will serve additionally as a guide to the moving 95 valve A' and connected parts.

The play of the auxiliary valve C may be limited by an adjustable stop E', here represented in the form of a screw, provided with a check-nut and passing inward through the 100 stop E.

Exhaust from the cylinder b takes place

when the secondary piston D is in the position shown in Fig. 2 through the flutings or channels of the spindle b² and the openings d'. The secondary piston D operates as a 5 valve, since when it is moved to the opposite extremity of its stroke to that represented in Fig. 2 communication with the passage d' is shut off. Openings e' are arranged in the stop E to prevent any undue compression during 10 the backward movement of the auxiliary valve C.

The secondary valve for admitting and exhausting the motive fluid to and from the space at the rear of the piston D is shown 15 more particularly in Figs. 3 and 4, where the valve-face is formed upon the extremity of the rod F, which passes outward through a suitable stuffing-box f on secondary-valve chest, which latter may consist of an extension of the bonnet forming cylinder b. Steam, &c., is admitted from the inlet-opening a of the main valve by the by-pass f' to the space at the rear of the valve-face on the rod F, and the space on the opposite side of the valve-seat is in communication with the space at the 25 rear of the piston D through the passage f².

The rod F is connected with the cylindrical block f³, working through a stuffing-box f⁴, by a reduced stem f⁵. The edge of the block f³ 30 acts as a sliding valve coöperating with the exhaust-passage f⁶, leading from the space surrounding the reduced stem f⁵ to the atmosphere. Normally or in the position shown in Fig. 3 the space at the rear of the piston 35 B is in communication with the atmosphere via this passage f⁶, and the main-valve head A' is kept upon its seat by the pressure of the live steam, &c., aided by a spring G, which surrounds the rod g, extending from 40 the piston D outwardly through the end of the cylinder d.

g' is a collar secured to the extremity of the rod g.

The stem H of the secondary valve may be 45 operated either mechanically or electrically. If the former method of operation is desired, there is provided a pivoted lever h, serving for the to-and-fro movement of the stem. If it is desired to operate the valve electrically, 50 one or more electromagnets H' are mounted adjacent to the stem in a suitable chamber and coöperative with an armature h', secured to the stem. The electromagnets are controlled by a suitable circuit H², which 55 comprise a battery h² and a suitable key h³. H² is a retracting-spring surrounding the stem. It is manifest from this construction of the secondary valve that the same is approximately balanced in all positions and there is 60 no position in which there is an excessive preponderance of pressure. A minimum effort is therefore required to operate the valve.

A fulcrumed lever I may be arranged to coöperate with the auxiliary valve C to effect 65 its movement from its seat if it is desired to operate it mechanically without the use of the secondary valve. Referring to the con-

struction set forth in the remaining figures, L represents a valve-casing provided with an inlet-opening l and an outlet-opening l'. 70 L' is a main-valve head connected by a stem l² with a piston L², fitted to a cylinder L³, formed on the valve-chest. M is an adjustable stop passing through the cylinder-head and against which the piston L² impinges 75 when the same is thrust backward to lift the valve L' from its seat. The spindle l³ passes outward through the wall of the valve-casing and is surrounded by a spring l⁴, impinging against the casing or a fixture thereof, and the collar l⁵, secured to the extremity of the spindle.

For the purpose of admitting or exhausting steam or other fluid to and from the space at the rear of the piston L², I have provided a 80 secondary valve comprising a rod N, whose extremity forms a valve-face, a reduced stem n, and a cylindrical block or piston n', which coöperates with the exhaust-passage n², as described with reference to the secondary 85 valve already set forth. This secondary valve may be operated in the manner there disclosed, or, instead of projecting the rod or piston n' through the head of the cylinder in which it works, the cylinder may at this 90 extremity be closed and the valve operated by means of a frame O, connecting the outer extremity of the rod N with an armature o, which moves to and fro along a rod o' and coöperates with the electromagnets O'. If 100 desired, a lever may be used for operating the frame O, as described with reference to Fig. 3.

o² designates a passage placing the space at the rear of the piston n' in communication 105 with the atmosphere. Furthermore, the main-valve head L' may itself be operated mechanically by a fulcrumed lever P.

o³ is a retracting-spring.

o⁴ is a passage leading from the space at the 110 rear of the piston L² to the space surrounding the stem n. A by-pass o⁵ connects the valve-inlet l with the space n⁶.

It will be seen in both forms of the device that there is a main-valve head whose movement to and from its seat is under the control of an actuating-piston, which in its turn is moved to and fro through the medium of a secondary valve, whose operation serves to control the admission and exhaust of steam or other fluid to and from the exposed face 115 of the actuating-piston, and, furthermore, that the secondary valve is essentially balanced and not subjected either in its closed or open position to excess of pressure in either 120 direction requiring an excessive effort to secure its movement.

Having described my invention, what I consider as new, and desire to secure by Letters Patent, is—

1. In a valve-actuating device the combination of a valve-casing, a valve-seat arranged therein, a main-valve head operating against the said seat, a piston suitably ar-

ranged in the said casing, a hollow stem connecting the said main-valve head and piston, a fluted spindle operating through the said stem, an auxiliary valve connected to one end of the said spindle, a secondary piston connected to the opposite end of the said spindle, and means adapted to pass a fluid-pressure against the said secondary piston, for operating the same thereby operating the secondary valve and causing the operation of the main-valve head, substantially as set forth.

2. In a valve-actuating device the combination of a valve-casing provided with suitable inlet and outlet ports, a valve-seat suitably arranged in the said casing, a main-valve head operating against the said seat, a cylinder *b* suitably connected to the said valve-casing, a piston operating therein, a hollow valve-stem connecting the said main-valve head and piston, a cylinder *d* connected to the cylinder *b*, a fluted spindle operating through the said hollow valve-stem and into the cylinder *d*, an auxiliary valve secured to one end of the said spindle, a secondary piston secured to the opposite end of the said spindle, and means adapted to pass a fluid-pressure against the said secondary piston, for operating the same thereby operating the secondary valve and causing the operation of the main-valve head, substantially as set forth.

3. In a valve-actuating device, the combination with a valve-casing, a valve-seat suitably arranged therein, a main-valve head normally in engagement with the said seat, a piston, a hollow stem connecting the said piston, an auxiliary valve, a valve-seat arranged on the one side of said main-valve head for the said auxiliary valve, a secondary piston, a fluted spindle operating through the said stem and connecting the auxiliary valve and secondary piston, and means adapted to pass a fluid-pressure against the said secondary piston for operating the same causing the auxiliary valve to move from its seat thereby operating the first-named piston and moving the main valve from its seat, substantially as set forth.

4. In a valve-actuating device, the combination of a valve-casing provided with suitable inlet and outlet ports, a valve-seat arranged therein, a main-valve head adapted to be normally in engagement with the said seat, a cylinder *b* suitably connected to the said casing, a piston operating therein, a hollow valve-stem connecting the said main-valve head and said piston, an auxiliary valve, a valve-seat arranged on the one side of the said main-valve head for the said auxiliary valve, a tubular extension formed integral with the said main-valve head on one side thereof provided with inlet-openings, a cylinder *d* connected to the cylinder *b*, a secondary piston operating therein, a fluted spindle operating through the said stem connecting the auxiliary valve and secondary

piston, and means for operating the same thereby operating the secondary valve causing the operation of the piston and moving the main valve from its seat, substantially as set forth.

5. In a valve-actuating device, the combination of a valve-casing provided with suitable inlet and outlet ports, a valve-seat arranged therein, a main-valve head adapted to be normally in engagement with the said seat, a cylinder *B* suitably connected to the said casing, a piston operating therein, a hollow valve-stem connecting the said main-valve head and said piston, an auxiliary valve, a valve-seat arranged in the one side of the said main-valve head for the said auxiliary valve, a tubular extension formed integral with the said main-valve head on one side thereof provided with inlet-openings, a cylinder *d* connected to the cylinder *b*, a secondary piston operating therein, a fluted spindle operating through the said stem connecting the auxiliary valve and secondary piston, an extension formed integral with the said cylinder *b*, the said extension provided with an inlet-port registering with the inlet-port of the valve-casing, said extension also provided with an outlet-port, connections between the said outlet-port and cylinder *b*, and a secondary valve arranged in the said extension adapted when operated to allow of pressure to enter the cylinder *d* and operate the secondary piston, substantially as set forth.

6. In a valve-actuating device, the combination of a valve-casing provided with suitable inlet and outlet ports, a valve-seat arranged therein, a main-valve head adapted to be normally in engagement with the said seat, a cylinder *b* suitably connected to the said casing, a piston operating therein, a hollow valve-stem connecting the said main-valve head and piston, an auxiliary valve, a valve-seat arranged in the one side of the said main-valve head for the said auxiliary valve, a tubular extension formed integral with the said main-valve head on one side thereof provided with inlet-openings, a cylinder *d* connected to the cylinder *b*, a secondary piston operating therein, a fluted spindle operating through the said stem connecting the auxiliary valve and secondary piston, an extension formed integral with the said cylinder *b*, the said extension provided with an inlet-port registering with the inlet-port of the valve-casing, said extension also provided with an outlet-port, connections between the said outlet-port and cylinder *b*, a secondary valve arranged in the said extension, and electrical means suitably connected thereto for operating the same to allow of pressure to enter the cylinder *d* and operate the secondary piston, substantially as set forth.

7. In a valve-actuating device, the combination of a valve-casing provided with suitable inlet and outlet ports, a valve-seat arranged therein, a main-valve head adapted to be normally in engagement with the said seat,

a cylinder *b* suitably connected to the said casing, a piston operating therein, a hollow valve-stem connecting the said main-valve head and said piston, an auxiliary valve, a valve-seat arranged in the one side of the said main-valve head for the said auxiliary valve, a tubular extension formed integral with the said main-valve head on one side thereof provided with inlet-openings, a cylinder *d* connected to the cylinder *b*, a secondary piston operating therein, a fluted spindle operating through the said stem connecting the auxiliary valve and secondary piston, an extension formed integral with the said cylinder *b*, the said extension provided with an inlet-port registering with the inlet-port of the valve-casing, said extension also provided with an outlet-port, connections between the said outlet-port and cylinder *b*, a rod *g* connected to one side of the said secondary piston and extending into the atmosphere, a resistance-spring mounted on the said rod, a cap connected to the outer end of the said rod, and means connected to the cylinder *d* for operating the said rod thereby operating the said secondary piston, substantially as set forth.

8. In a valve-actuating device, the combination of a valve-casing provided with suitable inlet and outlet ports, a valve-seat arranged therein, a main-valve head adapted to be normally in engagement with the said seat, a cylinder *b* suitably connected to the said casing, a piston operating therein, a hollow valve-stem connecting the said main-valve head and said piston, an auxiliary valve, a valve-seat arranged in the one side of the said main-valve head for the said auxiliary valve, a tubular extension formed integral with the said main-valve head on one side thereof provided with inlet-openings, a cylinder *d* connected to the cylinder *b*, a secondary piston operating therein, a fluted spindle operating through the said stem connecting the auxiliary valve and secondary piston, an extension formed integral with the said cylinder *b*, the said extension provided with an inlet-port registering with the inlet-port of the valve-casing, said extension also provided with an outlet-port, connections between the said outlet-port and cylinder *b*, a rod *g* connected to one side of the said secondary piston and extending into the atmosphere, a resistance-spring mounted on the said rod, a cap connected to the outer end of the said rod, means connected to the cylinder *d* for operating the said rod thereby operating the said secondary piston, substantially as set forth.

9. In a valve-actuating device, the combination of a valve-casing provided with suitable inlet and outlet ports, a valve-seat arranged therein, a main-valve head adapted to be normally in engagement with the said seat, a cylinder *b* suitably connected to the said casing, a piston operating therein, a hollow valve-stem connecting the said main-valve head and said piston, an auxiliary valve, a valve-seat arranged in the one side of the said main-valve head for the said auxiliary valve, a tubular extension formed integral with the said main-valve head on one side thereof provided with inlet-openings, a cylinder *d* connected to the cylinder *b*, a secondary piston operating therein, a fluted spindle operating through the said stem connecting the auxiliary valve and secondary piston, an extension formed integral with the said cylinder *b*, the said extension provided with an inlet-port registering with the inlet-port of the valve-casing, said extension also provided with an outlet-port, connections between the said outlet-port and cylinder *b*, a rod *g* connected to one side of the said secondary piston and extending into the atmosphere, a resistance-spring mounted on the said rod, a cap connected to the outer end of the said rod, means connected to the cylinder *d* for operating the said rod thereby operating the said secondary piston, substantially as set forth.

10. The combination of a main valve, a piston whose movement controls the movement of the main valve, a hollow valve-stem connecting the main valve with the piston, an auxiliary valve for controlling the flow of fluid to the piston, a secondary piston, and means for controlling the fluid for operating said secondary piston causing thereby the operation of the auxiliary and main valves, substantially as set forth.

and means arranged in the said cylinder *d* for exhausting the back pressure from the piston, substantially as set forth.

9. In a valve-actuating device, the combination of a valve-casing provided with suitable inlet and outlet ports, a valve-seat arranged therein, a main-valve head adapted to be normally in engagement with the said seat, a cylinder *b* suitably connected to the said casing, a piston operating therein, a hollow valve-stem connecting the said main-valve head and said piston, an auxiliary valve, a valve-seat arranged in the one side of the said main-valve head for the said auxiliary valve, a tubular extension formed integral with the said main-valve head on one side thereof provided with inlet-openings, a cylinder *d* connected to the cylinder *b*, a secondary piston operating therein, a fluted spindle operating through the said stem connecting the auxiliary valve and secondary piston, an extension formed integral with the said cylinder *b*, the said extension provided with an inlet-port registering with the inlet-port of the valve-casing, said extension also provided with an outlet-port, connections between the said outlet-port and cylinder *b*, a rod *g* connected to one side of the said secondary piston and extending into the atmosphere, a resistance-spring mounted on the said rod, a cap connected to the outer end of the said rod, means connected to the cylinder *d* for operating the said rod thereby operating the said secondary piston, substantially as set forth.

10. The combination of a main valve, a piston whose movement controls the movement of the main valve, a hollow valve-stem connecting the main valve with the piston, an auxiliary valve for controlling the flow of fluid to the piston, a secondary piston, and means for controlling the fluid for operating said secondary piston causing thereby the operation of the auxiliary and main valves, substantially as set forth.

In testimony whereof I have signed my name to this specification, in the presence of two subscribing witnesses, at Utica, in the county of Oneida and State of New York, this 21st day of May, 1898.
